CIRCUIT INTERRUPTING DEVICE

Herbert J. Crabbs, Wilkinsburg, Pa., assignor to
Westinghouse Electric & Manufacturing Company, East Pittsburgh, Pa., a corporation of Pennsylvania

Application November 12, 1937, Serial No. 174,202

12 Claims. (Cl. 200—145)

The invention relates to electrical circuit controlling devices in general and more particularly to air break circuit interrupting devices for high voltage circuits.

An object of the invention is the provision of an improved circuit interrupting device for high voltage circuits embodying means for controlling and extinguishing either large or small current arcs.

Another object of the invention is the provision of an improved circuit interrupter for high voltage circuits that is capable of safely interrupting currents from as low as a fraction of an ampere up to relatively high currents within its short circuit rating.

Another object of the invention is the provision of an improved circuit interrupting device embodying a plurality of pairs of serially connected separable contacts, an actuating member movable through a relatively short stroke for opening said pairs of contacts in a predetermined order, and arc extinguishing means associated with the contacts for extinguishing arcs of different current magnitude at different points of travel of the actuating member.

Another object of the invention is the provision of an improved circuit interrupting device of the type previously described that is simple and compact in construction, safe and reliable in operation, and inexpensive to manufacture.

The novel features that are considered characteristic of the invention are set forth in particular in the appended claims. The invention itself, however, both as to structure and operation, together with additional objects and advantages thereof, will best be understood from the following detailed description of several embodiments thereof when read in connection with the accompanying drawings, in which:

Figure 1 is a side elevational view, partly in section, of the circuit interrupting device constructed in accordance with the invention;

Fig. 2 is a bottom plan view of the device illustrated in Fig. 1;

Fig. 3 is a view similar to Fig. 1 illustrating the open circuit position of the interrupter;

Fig. 4 is a vertical sectional view of a modified form of the circuit interrupting device, illustrating the position of the parts in the closed circuit position of the device;

Fig. 5 is a sectional view similar to Fig. 4 illustrating the position of the parts in the first portion of an opening operation;

Fig. 6 is a sectional view similar to Figs. 4 and

5 illustrating the position of the parts in the full open circuit position of the device; and

Fig. 7 is an enlarged horizontal sectional view of the device shown in Fig. 4, the view being taken substantially on the line VII—VII thereof and looking in the direction of the arrows.

Referring to Figs. 1 to 3 of the drawings, the circuit interrupting device constructed in accordance with the invention comprises in general a

10 plurality of spaced hollow insulating tubes 9, 11 and 13, and a plurality of pairs of separable contacts consisting of the stationary contacts 15, 17 and 19 and the cooperating movable conducting plungers 21, 23 and 25. The hollow tubes 9, 11 and 13 are composed of a suitable fibrous material, such as hard fibre, which readily decomposes when acted on by an arc to give off a large quantity of deionizing or arc extinguishing gas which intermingles turbulently with the arc stream to

20 extinguish the same. The bores of the tubes 9, 11 and 13 are all of substantially the same diameter and have a relatively close fit with the movable plungers 21, 23 and 25. If desired, the tubes may be formed of other suitable insulating material and lined with an arc extinguishing material. The tubes are spaced and mechanically connected by a plurality of insulating plates 27, 29 and 31. A bracket 33 has its ends rigidly secured to the plates 29 and 31, and this bracket is adapted to be secured to any suitable form of support and insulated from ground for line potential. The upper end of the bore of the tube 9 flares outwardly, as indicated at 35, to form an enlarged mouth for the exit of gases formed

30 within the tube 9 during circuit interruption. The tubes 11 and 13 are of greater length than the tube 9, and the upper ends of these tubes are closed by suitable plugs 37 of insulating material, the plugs being retained in the upper ends of the 35 bores by means of pins 39.

The conducting plungers 21, 23 and 25 are disposed for axial movement in the bores of the tubes 9, 11 and 13, respectively, and the plungers all have substantially the same diameter or cross section. The diameter of the conducting plungers is slightly less than the diameter of the bore of the tubes by an amount sufficient to permit free axial movement of the plungers within the tubes. The lower ends of the conducting plungers are mechanically connected for movement together by means of a tie plate 41 of insulating material. The lower ends of the plungers are reduced and pass through openings 43 provided therefor in the tie plate 41. The lower ends of the reduced portions of the plungers are thread-

ed for receiving the clamping nuts 45, which serve to secure the plungers to the tie plate 41. The length of the conducting plunger 21 is substantially the same as the length of its corresponding insulating tube 9, so that the upper end of the plunger lies substantially in the plane of the upper edge of the tube 9 in the closed circuit position of the device. The conducting plungers 23 and 25 are of greater length than the plunger 21 for a purpose which will be hereinafter described.

The stationary contact 15, which cooperates with the plunger 21, is secured to the end of a strip 47 of resilient conducting material, the opposite end of which is secured to the offset portion 49 of a bracket 51 by means of a bolt 53 and a nut 55. The bolt 53 serves as a terminal bolt for connecting the stationary contact 15 and the resilient strip 47 to the conductor 57 of an electrical circuit. The bracket 51 is secured to and supported by the insulating tube 9 in any suitable manner.

The stationary contacts 17 and 19, which cooperate with the conducting plungers 23 and 25, are mounted within an insulating tubular contact holder 59, which is threaded at each end into the tubes 11 and 13. The contacts 17 and 19 are slidably mounted in the contact holder 59, and are biased outwardly of the holder by means of a light coil spring 61. The spring 61 serves to bias the contact 17 into engagement with the side of the conducting plunger 23, and the contact 19 into engagement with the side of its cooperating conducting plunger 25. The contacts 17 and 19 are electrically connected by means of a flexible shunt conductor 63.

The contact holder 61 and the stationary contacts 17 and 19 mounted therein are disposed substantially intermediate the length of the insulating tubes 11 and 13, and the lengths of the conducting plungers 23 and 25 are such that a portion of these plungers extends above the contacts 17 and 19, so that the contacts 17 and 19 remain in engagement with their corresponding conducting plungers 23 and 25 during the first portion of the opening movement of the plungers after the plunger 21 has separated a predetermined distance from its stationary contact 15.

The conducting plungers 23 and 25 are each provided with a follower 62 of insulating material. The followers 62 may be formed of the same insulating material as the tubes 9, 11 and 13, and each follower is provided with a reduced portion 64, which serves to restrict the arc passages in the bores of the tubes 11 and 13, as will be described hereinafter.

A terminal bushing 65 is threaded into the tubular member 13 adjacent its lower end, in which is mounted a spring-pressed contact 67 (Fig. 2). The contact 67 is biased inwardly into engagement with the side of the conducting plunger 25 by means of a coil spring 69. The terminal bushing 65 is provided with a threaded terminal stud 71 for receiving a terminal nut 73, the stud 71 and nut 73 forming a second terminal for connecting the device in an electrical circuit.

The electrical circuit through the interrupter extends from the right-hand terminal 53 through the resilient strip 47, stationary contact 15, conducting plunger 21, through a bridging strip 75 of conducting material to the conducting plunger 23, stationary contact 17, flexible shunt 63, stationary contact 19, the conducting plunger 25 to the stationary terminal contact 67 and terminal stud 71.

The tie plate 41, which serves to mechanically connect the conducting plungers for movement together, has a pair of operating eye plates 77 secured to the opposite side thereof. The plates 77 are provided with aligned openings 79 for connection to a suitable operating member (not shown).

The conducting plungers 21, 23 and 25 are biased downwardly to open circuit position by means of tension springs 91, the upper ends of which are secured to the eye plates 77.

The conducting plungers are releasably held in closed circuit position, as illustrated in Fig. 1, by means of a trip device indicated generally at 83. The tie plate 41 is provided with a latch piece 85, which is adapted to normally be engaged by a latch member 87 to hold the interrupter in closed circuit position. The latch member 87 is connected for movement with the movable core 89 of the solenoid 91, and is biased to latching position, as shown in Fig. 1, by means of spring 93. The solenoid 91 is carried by a bracket 95 which is secured to the insulating plate 27. The solenoid 91 may be made responsive to any one of a plurality of abnormal electrical conditions in the circuit to be controlled to trip the interrupter, or its energization may be controlled manually from some remote point.

The operation of the interrupter as thus far described is briefly as follows: Upon energization of the trip device 83, the tie plate 41 is released, and the biasing spring 81 moves the tie plate 41 and all of the conducting plungers 21, 23 and 25 in a downward direction to open circuit position. The downward movement of the conducting plungers first causes the plunger 21 to separate from its stationary contact 15. During this portion of the downward movement of the plungers, the contacts 17 and 19 still engage the upper portions of the conducting plungers 23 and 25. Continued downward movement of the plungers after the plunger 21 has separated a predetermined distance from its stationary contact 15 causes the conducting plungers 23 and 25 to disengage and separate from the stationary contacts 17 and 19 to introduce additional gaps in the circuit. The full open circuit position of the plungers is illustrated in Fig. 3.

During the above-described circuit opening operation, an arc is first drawn between the conducting plunger 21 and the stationary contact 15. If this arc is not extinguished in the insulating tube 9 by the time the plungers 23 and 25 begin to separate from their stationary contacts 17 and 19, additional arcs are drawn between these plungers and their corresponding stationary contacts.

The bores of the insulating tubes 9, 11 and 13 form arc chambers or passages for the arcs drawn between the plungers and their corresponding stationary contacts. The dimension of the arc passage formed by the bore of the tube 9 is such that arcs of high current magnitude are effectively extinguished therein before the conducting plungers 23 and 25 separate from their corresponding stationary contacts 17 and 19. This results from the fact that arcs of high current magnitude are of such size as to intimately engage the inner surface of the bore of the tube 9 so that a sufficient amount of arc extinguishing gas is given off by the action of the arc on the bore of the tube 9 to effectively extinguish the arc. The dimension of the bore of the tube 9 and the enlarged mouth 25 prevent the pressure developed by the arc gases within the bore of

the tube 9 from becoming large enough to damage this tube. If the arc drawn between the plunger 21 and the stationary contact 15 is of lower current magnitude, it may not be extinguished within the tube 9. This is due to the fact that the arcs of lower current magnitude are smaller and may not play upon the inner surface of the tube 9 so as to produce a sufficient quantity of arc extinguishing gas to extinguish these arcs. In such instance, additional arcs will be drawn between the conducting plungers 23 and 25 and the stationary contacts 17 and 19. When these plungers separate from their contacts, the reduced portions 64 of the followers 62, connected to the upper ends of the conducting plungers 23 and 25, serve to restrict and confine the arcs drawn between the plungers 23 and 25 and the stationary contacts 17 and 19, causing the arcs to intimately engage the inner surface of the tubes 11 and 13, and also the surfaces of the followers 62. Due to the confinement of these arcs and the intimate engagement thereof with the material of the tubes 11 and 13 and the followers 62, a sufficient quantity of arc extinguishing gas is liberated to effectively extinguish arcs of a current magnitude within a certain range below high magnitude currents. If the arcs are of a current magnitude so low that they are not extinguished by the partial confinement provided by the reduced portions 64 of the followers 62, the continued downward movement of the plungers during the latter part of the opening operation brings the unreduced upper portions of the followers 62 into engagement with the stationary contacts 17 and 19. The unreduced upper portions of the followers serve to further restrict and confine the arc passages and the arcs to produce a sufficient deionizing action to effectively extinguish these low current arcs. It will thus be seen that arcs of high current magnitude are effectively extinguished in the tube 9 between the plunger 21 and the stationary contact 15, and arcs of lower current magnitude are effectively extinguished within the tubes 11 and 13.

The insulating tubes 11 and 13 are provided with vents 101 and 103 to relieve the pressure of the arc gases. It will be noted that vents 101 in the tube 11 direct the arc gases in a different direction from the direction given by the vents 103 in the tube 13, while the arc gases developed in the tube 9 are directed in still another direction. This arrangement of the vents minimizes the possibility of trouble from the arc gases uniting to cause an external flashover.

The plungers 21 and 23 are at the same potential but the plungers 23 and 25 in the open position of the device have a difference of potential between them. In order to prevent any arc gases that may be forced out of the lower ends of the tubes 11 and 13 from intermingling and causing an external flashover, a barrier 105 is provided. The barrier 105 is secured at its lower end to the tie plate 41 for movement therewith, and is of a length such that its upper portion lies between the lower ends of the tubes 11 and 13 in the open circuit position of the device.

If desired, the interrupting device previously described may be used in connection with a disconnect or air break switch, so as to interrupt the circuit and extinguish the arc before the switch blade opens. In such instance, the interrupting device may be associated with the switch in substantially the same manner as the inter-

rupting device disclosed in the copending application of S. T. Schofield and J. H. Frakes, Serial No. 126,890, filed February 20, 1937, and assigned to the assignee of this invention, now Patent 2,172,225, issued September 5, 1939. In such combination, the trip device 83 would, of course, be omitted and the interrupter biased to closed circuit position and provided with a hook to be engaged by the actuator carried by the switch blade as in the case of the interrupter disclosed in the aforementioned copending application of S. T. Schofield, et al.

A modified form of the circuit interrupter is illustrated in Figs. 4 through 7 of the drawings.

- 15 In this modification of the invention, the stationary contacts and movable conducting members are carried by and disposed in a single insulating tube, thus eliminating the danger of adjacent arcs causing an external flashover. Referring to Figs. 4 through 7 of the drawings, the circuit interrupter illustrated comprises in general a hollow insulating tube 107, a plurality of stationary contacts 109, 111 and 113, and a circuit controlling plunger or member 115, which has a plurality of contact members or conducting sections 117, 119 and 121 which cooperate with the stationary contacts 109, 111 and 113 to form a plurality of pairs of separable contacts. The hollow insulating tube 107 is composed of a fibrous insulating material, such as hard fibre, which, when acted on by an arc, gives off large quantities of deionizing or arc extinguishing gases to extinguish the arc. If desired, the insulating tube 107 may be composed of other insulating materials and lined with a material which gives off an arc extinguishing gas. The tube 107 is enclosed and protected by an outer insulating tube 123 which is secured to the inner tube 107 in any suitable manner.
- 20 The circuit controlling plunger or member 115 is disposed for axial movement within the bore of the tube 107, and its diameter is slightly less than that of the bore so as to permit free axial movement thereof within the bore. The conducting sections 117, 119 and 121 are insulated
- 25 from one another by the sections or followers 125, which are composed of a suitable insulating material similar to the material of the tube 107. The insulating followers 125 are threadedly connected at each end to the conducting sections or contact members 117, 119 and 121.

- 30 The stationary contact 109, which cooperates with the contact member 117, is carried by one end of a strip 127 of resilient conducting material, the opposite end of which is secured to a bracket 129 by means of a terminal bolt 131 and nut 133. The terminal bolt 131 forms one terminal of the interrupter and serves to connect the interrupter to a conductor 135 of an external circuit.

- 35 The upper end of the bore of the tube 107 is flared outwardly, as indicated at 137, to provide an enlarged mouth adjacent the stationary contact 109 for the exit of gases produced by the arc between the contact member 117 and the stationary contact 109.

- 40 The stationary contacts 111 and 113, which cooperate with the contact members 119 and 121, respectively, are disposed within suitable transverse openings provided therefor in the insulating tube 107, and these contacts are biased to engage their corresponding contact members by means of springs 139. The contact members 117, 119 and 121 engage their corresponding stationary contacts 109, 111 and 113 in the closed circuit

position of the interrupter, as is illustrated in Fig. 4. The stationary contacts 111 and 113 are so disposed in the tube 107 that in the closed circuit position of the interrupter they engage their corresponding contact members 119 and 121 a predetermined distance below the upper ends of these contact members, so that during opening movement of the member 115, the contact member 117 first separates from its stationary contact 109, during which time the stationary contacts 111 and 113 still remain in engagement with their corresponding contact members 119 and 121, respectively. At a later point in the opening movement of the member 115, the contact members 119 and 121 separate from their corresponding stationary contacts 111 and 113.

The plurality of pairs of separable contacts formed by the stationary contacts 109, 111 and 113 and the movable contact members 117, 119 and 121 are connected in series circuit relationship by means of the contacts 141 and 143 and the bridging contact strips 145 and 147. The stationary contacts 141 and 143 are mounted in suitable transverse openings provided therefor in the insulating tube 107, and are biased to engage the contact members 117 and 119, respectively, by means of the springs 149. The contact 141 is so disposed that it engages the contact member 117 throughout its range of movement from closed to open circuit position, and likewise the contact 143 is so disposed as to engage the contact member 119 throughout its range of movement from closed to open circuit position. The contact 141 is electrically connected to the stationary contact 111 by means of the conducting strip 145, and the stationary contact 143 is electrically connected to the stationary contact 113 by the conducting strip 147. The movable contact members 117, 119 and 121 all have substantially the same cross sectional area.

An operating eye 151 is threaded on the lower end of the lowermost contact member 121, and this eye is provided with a terminal means 153 which forms the opposite terminal of the interrupter. The circuit controlling member 115 is biased downwardly to open circuit position by means of a tension spring 155 which is connected at its upper end to the operating eye 151.

The circuit controlling member 115 is adapted to be releasably held in closed circuit position, as shown in Fig. 4, by means of an electro-responsive trip device indicated generally at 157. The trip device comprises a latch piece 159 carried by the operating eye 151 and a latch member 161 for normally engaging the latch piece. The latch member 161 is connected to the movable core 163 of a trip solenoid 165 and is biased to latching position by means of a spring 167. The latch controlling solenoid 165 may be made responsive to any abnormal circuit condition so as to trip the interrupter in response to predetermined conditions.

The operating eye 151 is adapted to be connected to a suitable operating member for closing the interrupter.

The electrical circuit through the interrupter extends from the upper terminal bolt 131 through the stationary contact 109, the contact member 117, stationary contact 141, conducting strip 145, stationary contact 111, contact member 119, stationary contact 143, conducting strip 147, stationary contact 113, and the contact member 121 to the opposite terminal 153.

The operation of the interrupter is briefly as follows: Upon energization of the trip device 157,

the operating eye 151 is released and the circuit controlling member 115 is moved downwardly to open circuit position by means of the spring 155. During the first part of the opening movement of the member 115, the contact member 117 separates from its stationary contact 109. During this portion of the opening movement, the contacts 111 and 113 remain in engagement with the upper portions of their corresponding contact members 119 and 121. At a later point in the opening movement of the member 115, contact members 119 and 121 separate from their corresponding stationary contacts 111 and 113 to introduce additional gaps in the circuit, as shown in Fig. 5. The final full open circuit position of the circuit controlling member 115 is illustrated in Fig. 6.

During the opening movement of the circuit controlling member 115, an arc is first drawn between the contact member 117 and its stationary contact 109. If this arc is not extinguished before the contact members 119 and 121 separate from their stationary contacts 111 and 113, additional arcs in series are drawn between the contact members 119 and 121 and their stationary contacts 111 and 113 during the latter part of the opening movement when these contact members separate from their stationary contacts.

The arc extinguishing operations of this modification of the circuit interrupter are substantially identical to the arc extinguishing operations of the originally described embodiment. Arcs of high current magnitude are effectively extinguished between the contact member 117 and the stationary contact 109 in the first part of the opening movement of the circuit controlling member prior to separation of the contact members 119 and 121 from their stationary contacts 111 and 113. Arcs of lower current magnitude drawn between the contact members 119 and 121 and their corresponding stationary contacts are extinguished during the latter part of the opening operation. This results from the fact that the followers 125, which are provided with reduced portions 169, provide restricted arc passages for the arcs drawn between the contact members 119 and 121 and their corresponding stationary contacts.

The insulating tube 107 and the outer tube are provided with suitable vents 171 adjacent the contacts 111 and 113 to provide an exit for the gases formed during arcing.

In both of the embodiments of the invention previously described, it will be noted that the actuating member moves through a relatively short stroke from closed to open circuit position to effect the separation of the plurality of pairs of contacts in a predetermined order, and arcs of high current magnitude are extinguished during the initial portion of the opening movement, while arcs of lower current magnitude are extinguished during a later part of the opening movement. With the proper selection of stroke and dimensions of the arc passages, the interrupter will control and interrupt currents from a fraction of an ampere up to the short circuit interrupting ability of the device. The number of pairs of separable contacts may be increased or decreased to suit the particular requirements of the device.

While the invention has been disclosed in accordance with the provisions of the patent statutes, it is to be understood that various changes in the structural details thereof may be made without departing from the spirit of

the invention. It is desired, therefore, that the language of the appended claims be given the broadest reasonable construction permissible in view of the prior art.

I claim as my invention:

1. In a circuit interrupting device, a plurality of pairs of separable contacts connected in series in the circuit to be interrupted, means including an actuating member movable through a relatively short stroke for first opening one of said pairs of contacts and thereafter opening the remaining pairs of contacts, means forming arcing passages adjacent each pair of contacts, the inner surface of the passages being of a material which gives off a large quantity of gas when acted on by an arc, the construction and dimension of the arc passage for the pair of contacts which are first opened being such as to extinguish high current arcs between said pair of contacts to finally interrupt the circuit upon short circuit or heavy overload, and the construction and dimension of the passages adjacent the remaining pairs of contacts being such as to extinguish lower current arcs.

2. In a circuit interrupter, a plurality of pairs of separable contacts connected in series in the circuit to be interrupted, means including an actuating member operable to first separate one of said pairs of contacts and thereafter separate the remaining pairs of contacts, means enclosing the paths of movement of said contacts having its inner portion of a material which gives off a deionizing gas when acted on by an arc, the enclosing means adjacent the pair of contacts which are first separated serving to extinguish arcs above a predetermined current magnitude to finally interrupt the circuit upon short circuit or heavy overload, means restricting the arcs of lower current magnitude drawn between the remaining pairs of contacts and causing said arcs to intimately engage the inner portion of the enclosing means to effect extinguishment thereof.

3. In a circuit interrupter, a plurality of pairs of separable contacts connected in series in the circuit, means including an actuating member operable to first separate one of said pairs of contacts and thereafter separate the remaining pairs of contacts, means enclosing the path of movement of said movable contacts, the inner portion of said means being of a material which gives off a deionizing gas when acted on by an arc, the enclosing means adjacent the pair of contacts which are first separated serving to extinguish arcs in excess of a predetermined current magnitude to finally interrupt the circuit upon short circuit or heavy overload, and insulating followers movable with the movable contacts of the remaining pairs of contacts, said followers restricting the arcs of lower current magnitude and forcing the arcs into intimate contact with the inner portion of the enclosing means to effect extinguishment thereof.

4. In a circuit interrupter, a plurality of hollow tubes the inner portions of which are of a material which gives off a deionizing gas when acted on by an arc, a conducting plunger movable in each tube, means for simultaneously moving all of said plungers to open and to closed circuit position, a plurality of stationary contacts one for each plunger disposed so that during a circuit opening operation one of said plungers first disengages its stationary contact and thereafter the remaining plunger disengages its stationary contact, an insulating follower movable

75 with said remaining plunger to restrict the arc drawn thereby, and means connecting said contacts and plungers in series in the circuit.

5. In a circuit interrupter, a single hollow tubular member, the inner portion of which is of a material which gives off a deionizing gas when acted on by an arc, a circuit controlling member movable in said tubular member to open and to closed circuit position, said member having a plurality of conducting sections separated and insulated from one another by insulating sections, a plurality of stationary contacts, at least one for each conducting section, engaged by said conducting sections in the closed position of the circuit controlling member, said contacts being disposed so that during a circuit opening operation one of said conducting sections first separates from its stationary contact and at later points the remaining conducting sections separate from their corresponding contacts.

6. In a circuit interrupter, a plurality of hollow tubes the inner portions of which are of a material which gives off a deionizing gas when acted on by an arc, a conducting plunger movable in each tube, means for simultaneously moving all of said plungers to open and to closed circuit position, a plurality of stationary contacts one for each plunger disposed so that during a circuit opening operation one of said plungers first disengages its stationary contact and thereafter the remaining plungers disengage their stationary contacts, insulating followers movable with said remaining plungers to restrict the arcs drawn thereby, and means connecting said contacts and plungers in series in the circuit, said tubes being vented in different directions for exit of the arc gases.

7. In a circuit interrupting device, means forming a plurality of confining arc chambers of substantially the same cross sectional area, means comprising a plurality of movable contact members one in each chamber electrically connected in series in the circuit and operable to first draw an arc in one of said chambers and then draw an arc in the other of said chambers if the arc in said first chamber has not been extinguished, said contact members all having substantially the same cross sectional area, and means for restricting the arc drawn in the aforementioned other chamber to cause interruption of low current arcs therein.

8. In a circuit interrupter, means forming a plurality of confining arc chambers all substantially of the same cross section, a stationary contact and a cooperating movable contact member for each chamber, said contact members being electrically connected in series in the circuit and all having substantially the same cross sectional area, an actuating member movable to first cause separation of one of said movable contact members from its stationary contact and for thereafter causing separation of the other movable contact member from its stationary contact, and a follower connected to said other movable contact member for restricting the arc drawn thereby.

9. In a device for interrupting an electrical circuit, means forming a plurality of confining arc passages, the first of said passages being relatively wide for extinguishing high current arcs to finally interrupt the circuit when the magnitude of the current is large, and the other of said passages being relatively narrow for extinguishing lower current arcs, and means connected in series in the circuit to be interrupted

for first drawing an arc in said first passage and for then drawing arcs in the other passage if the arc continues in said first passage.

10. In a device for interrupting an electrical circuit, means forming a plurality of arc passages of different arc extinguishing ability, said passages having the interior thereof of a solid material which when acted on by an arc gives off a volume of arc extinguishing gas, means electrically connected in series in the circuit to be interrupted for causing arcs in said passages, one of said passages being of relatively large cross section for interrupting large current arcs to finally interrupt the circuit when the magnitude of the current is large, and the other passage being of relatively small cross section to interrupt arcs of lower current magnitude.

11. In a device for interrupting an electrical circuit, a plurality of pairs of separable contacts connected in series in the circuit to be interrupted, an actuating member movable through a relatively short stroke for first opening one pair of said contacts and for thereafter opening the remaining pairs of said contacts, means associated with said contacts forming a plurality

of arc passages one for each pair of contacts, the passage for the pair of contacts which are first opened being of relatively large cross section for interrupting large current arcs to finally interrupt the circuit when the magnitude of the current is large, and the other passages being of relatively small cross section to interrupt arcs of lower current magnitude.

12. In a circuit interrupter, a plurality of pairs 10 of separable contacts connected in series in the circuit to be interrupted, means including an actuating member operable through a relatively short stroke for first opening one pair of said contacts and for thereafter opening the other 15 pairs of said contacts, an arc extinguishing structure associated with said contacts forming a relatively wide arc passage for said pair of contacts which are first opened for extinguishing large current arcs to finally interrupt the circuit when the magnitude of the current is large, and forming narrow arc passages at said other pairs of contacts for extinguishing lower current arcs.

HERBERT J. CRABBS.
